CONVERSION OF OILS

Charles W. Tyson, Summit, and Carl O. Tongberg,
Westfield, N. J., assignors to Standard Oil De-
velopment Company, a corporation of Delaware

Application June 12, 1940, Serial No. 340,070

4 Claims. (Cl. 196—52)

This invention relates to the conversion of hydrocarbon oils and pertains more particularly to the conversion of such oils in the presence of finely divided solid catalytic material which is subjected to frequent regenerations.

While the invention in some of its broader phases has a more general application such as in processes involving the reforming, dehydrogenation, polymerization, alkylation and isomerization of hydrocarbon oils and also in the purifying and refining of such oils, it finds particular application in the cracking of higher boiling hydrocarbons into lower boiling constituents suitable for motor fuel.

It has heretofore been proposed to crack hydrocarbon oils by suspending finely divided cracking catalysts in a stream of oil to be cracked and then passing the resulting stream through a cracking zone maintained at the desired cracking temperature. When operating in this manner the cracked products containing the catalyst in suspension after passing through the cracking zone are first transferred through suitable separators for segregating the powdered catalytic material from the cracked products. The cracked products are then fractionated to separate the motor fuel fraction from insufficiently cracked constituents and gases. The finely divided catalytic material after passing one or more times through the cracking zone is passed through a regenerating zone in which an oxidizing atmosphere is maintained to burn off carbonaceous and other combustible deposits which form during the cracking process and which tend to reduce the activity of the catalyst. One method of regenerating such finely divided catalytic material is to suspend the catalyst recovered from the separators in a stream of gas and pass the resulting stream through a regenerating zone in which an oxidizing atmosphere is maintained under conditions such as to burn the carbonaceous deposits from the catalyst. The stream of regenerating gas and catalyst after passing through the regenerating zone is then transferred to suitable separators of the same or different type than those employed in segregating the catalyst from the cracked products. The regenerated catalyst separated from the regenerated gas in the separators is then returned to the cracking process for reuse.

This method of regenerating combined with powdered catalyst cracking offers a number of advantages resulting in lower equipment and operating costs.

In order to obtain maximum efficiency from a combination process above described it has heretofore been considered desirable to maintain a

differential pressure between the cracking and regenerating portions of the equipment. For example experience has shown that, in most cases at least, the maintenance of a substantial superatmospheric pressure in the cracking zone results in excessive formation of coke on the catalyst and also changes the characteristics of the motor fuel produced. On the other hand the use of a substantial superatmospheric pressure in the regeneration portion of the equipment permits better control of the regenerating temperature and reduces the size of the equipment.

Practical difficulties have been encountered however in devising operating equipment which will transfer the finely divided catalytic material from the zone of lower pressure such as that employed in the cracking circuit into a zone of higher pressure such as is employed in the regenerating circuit. By way of example, if a compression screw or other mechanical means is employed for imposing the desired pressure on the catalyst it has been found that the power requirement increases with the difference of pressure across the compression screw. Furthermore a high pressure differential across the screw tends to increase wear and erosion on the screw and tends to increase maintenance costs.

Also serious operating difficulties have been encountered in releasing the pressure on the catalyst stream between the regenerating and cracking zone. Attempts made to release the pressure by means of rotary star feeders, Venturi tubes, release valves and other similar mechanical means have not proven wholly successful. In case of the star-feeders, for example, difficulty has been encountered in regulating the flow catalyst through the feeder. Due to the finely divided nature of the catalyst, a considerable portion passed through the clearances in the feeder and around the empty return pockets in the feeder. In the case of restricted openings, such as Venturi tubes, the catalyst tends to bridge across the restricted openings and plug the lines. Release valves are subject to the same objection as the Venturi tubes and further introduces erosion problems.

Among the objects of the present invention is to provide a method of overcoming the difficulties above-mentioned and to provide a process wherein in the cracking and regenerating portions of the equipment may be operated under substantially the same pressure without the inherent objections previously attending such operations.

Other objects and advantages of the invention will be apparent from the more detailed description hereinafter.

It has been discovered as a result of extensive

research and investigation that the increase in the formation of coke on the catalyst normally resulting from increase in the pressure is not dependent upon the total pressure in the cracking circuit but rather on the partial pressure on the oil vapors therein and that the cracking operation may be operated under substantial pressures without giving rise to increased coke formation providing the partial pressure of the oil vapors is not correspondingly increased. For example it has been found that substantially the same results can be obtained with respect to the amount of coke formed when cracking under super-atmospheric pressure as when cracking at atmospheric pressure providing the partial pressure of the oil vapors is the same in both cases. The total pressure in the cracking circuit may be increased without increasing the partial pressure of the oil vapors by introducing a diluent or inert gas. Such gas may for example be steam or it may be a gas capable of undergoing reactions other than cracking such as capable of undergoing polymerization, alkylation, isomerization, etc. While steam, due to its availability and cost is preferred, other gases such as those formed during the cracking operation may be employed.

Having set forth the general nature and objects, the invention will be better understood by referring to the accompanying drawing which is partly diagrammatic and partly schematic of an apparatus capable of carrying the invention into effect.

Referring to the drawing, a numeral 10 designates a charge line through which the oil to be cracked is introduced into the system. Such oil may comprise a clean condensate stock such as a gas oil or it may be a residual stock such as a topped or reduced crude. The oil introduced through the line 10 is forced by pump 11 through a heating coil 12 located in furnace 13 wherein it is heated to a temperature sufficient to vaporize at least a substantial portion of the oil. The temperature and time of contact of the oil within the heating coil 12 is preferably controlled to obtain the desired degree of vaporization without any substantial amount of thermal cracking. If desired steam or other diluent gas may be introduced into the oil passing to the vaporizing coil through line 14.

The oil after passing through the vaporizing coil 12 is conveyed through transfer line 15 to a separator 16 wherein vapors separate from the unvaporized residue. Steam or other diluent gas may be introduced into the bottom of the separator 16 through line 17. Unvaporized residue separated in the separator 16 may be withdrawn from the bottom thereof through line 18. Vapors liberated in the separator 16 pass overhead through line 19 to an injector 20 in which finely divided catalytic material is introduced into the stream.

In cases where a clean condensate stock is employed for cracking the separator 16 may be omitted or the products from the vaporizing coil 12 may be passed around the separator through line 21.

A catalyst introduced into the oil vapors in the injector 20 may be any suitable catalyst capable of accelerating or bringing about desired cracking operation. Such catalysts may comprise for example the naturally active or activated clays or synthetic adsorptive materials of the same or different chemical composition.

The relative amount of catalyst introduced into the oil vapors is dependent upon the activity

of the catalyst, the nature of the oil to be cracked, the temperature of the cracking operation, the degree of conversion desired and other factors. In general the relative amount of catalyst to oil vapors may range between .5 up to 20 or more parts of catalyst per part of oil.

The suspension of oil vapors, inert gas, and finely divided catalyst formed in the injector 20 passes through line 22 to a cracking reactor 23. The reactor 23 may be of any suitable design capable of maintaining the catalyst in suspension within the gas stream and for giving the required time for obtaining the conversion. As illustrated, the reactor 23 is shown in the form of a vertical tower which is preferably insulated to avoid radiation losses. It will be understood however that any other type of apparatus such as fired or unfired coils, baffle towers or the like may be substituted in its stead.

The suspension after passing through the reactor 23 in which the cracking operation is accomplished is transferred through line 24 to suitable equipment for separation of the catalyst from the cracked products. Such equipment may for example comprise a plurality of cyclone separators 25, 26 and 27 connected in series through lines 28 and 29. Catalyst separated in the initial cyclone separator 25 is removed from the bottom thereof through conduit 31 and passed to a catalyst hopper 32. If desired steam or other stripping gas may be introduced into the stream of catalyst passing through the catalyst hopper 32 through line 33 for removing volatile hydrocarbon constituents remaining in the catalyst.

The cracked products, after having the bulk of the catalytic material removed therefrom in the initial cyclone separator 25, pass through line 28 to the secondary cyclone separator 26 in which further separation is accomplished. The catalyst separated in the secondary separator 26 passes to the catalyst hopper 32 through line 34.

Cracked products after being further purified of powdered material in the secondary cyclone separator 26 pass through line 29 to the tertiary or final cyclone separator 27 for further purification and removal of powdered material therefrom. Powdered material recovered in the final separator 27 is transferred to the catalyst hopper 32 through line 35.

A line 36 is preferably provided connecting the top of the catalyst hopper 32 with the line 28 leading from the primary separator 25 to the secondary separator 26 so that gases collecting in the top of the catalyst hopper may be recombined with the cracked products.

The cracked products from the final separator 27 pass through line 37 to a fractionating tower 38 wherein the products are fractionated to separately condense insufficiently cracked constituents. Condensate formed in the fractionating tower 38 may be withdrawn from the bottom thereof through line 39 and returned to the cracking circuit for further cracking treatment or treated in any desired manner outside of the purpose of the present invention.

Vapors remaining uncondensed in the fractionating tower 38 pass through line 41 to a condenser 42 wherein the desired motor fuel distillate is condensed. Products from the condenser 42 pass through a receiver 43 wherein the desired distillate separates from uncondensed gases. Gases separated in the receiver 43 are removed therefrom through line 44 having a release valve

45 for imposing the desired back pressure on the system. The gases so released may be passed to a suitable recovery system (not shown) for removal of any gasoline constituents which may be contained therein.

A catalyst separated from the cracked products and collected in the catalyst hopper 32 is transferred through line 46 having a suitable feeding mechanism such as a star feeder 47 into a screw conveyor 48.

The screw conveyor 48 may be of compression type capable of building up at least a portion of the pressure necessary to overcome the resistance of the system. In commercial size units of this type the pressure drop through the cracking and regenerating systems under normal operations may be of the order of from 10 to 30 pounds. The pressure on the catalyst necessary to overcome this resistance may be supplied by the screw conveyor 48 or additional screw conveyors or other pressure providing means may be included in the circuit as later described.

The catalyst passes from the screw conveyor 48 into an injector chamber 49 wherein it is picked up by a stream of regenerating gas introduced through line 50. The injector chamber may be of any desired construction which will permit intimate mixing of catalyst and regenerating gas. As illustrated, the chamber is provided with a conical disc having a central pipe through which the catalyst discharges into a mixing chamber located below the partition. The regenerating gas is preferably an oxidizing gas and may be air or air diluted with other gases such as steam, spent combustion gases or the like.

The suspension of unregenerated catalyst and regenerating gas passes from the injector 49 through line 51 to a regenerating chamber 52 maintained at the desired temperature for burning the carbonaceous deposits formed during the cracking operation from the catalyst. The temperature within the regenerating chamber should be controlled to avoid deactivating the catalyst. When activated clays are employed such as for example acid treated bentonitic clays the temperature within the regenerating chamber should preferably be maintained below 1100° F. This temperature can be controlled by regulating the relative amounts of catalyst and oxidizing gas passing through the reaction chamber, by the provision of internal cooling elements within the regenerating chamber or in any other suitable manner.

The suspension of regenerating gas and catalyst after passing through the regenerating chamber 52 passes through line 53 to a primary cyclone separator 54 in which the bulk of the regenerated catalyst is separated from the regenerating gas. The catalyst so separated is transferred through conduit 55 to a second catalyst hopper 56. Steam may be introduced into line 55 to strip regeneration gases from the powdered catalyst.

The regenerating gas after having the bulk of the catalytic material removed therefrom in the primary cyclone separator 54 passes through line 57 to a secondary cyclone separator 58 wherein further separation is accomplished. Catalyst separated in the secondary separator 58 is transferred through line 59 to the catalyst hopper 56. Regenerating gas after being further purified in the secondary separator 58 is transferred through line 60 to a third cyclone separator 61 wherein final purification is accomplished. The catalyst

separated in the final cyclone separator 61 is transferred through conduit 62 to the catalyst hopper 56. The regenerating gas after having been substantially purified of regenerated catalyst in the final separator 61 is rejected from the system through line 63. This gas may be expanded through a turbine or it may be passed through suitable heat recovery system for removal of heat contained therein.

10 The regenerated catalyst collected in the catalyst hopper 56 is passed through line 64 having a suitable feeding mechanism such as a star feeder 65 which feeds the material at the desired rate into a screw conveyor 66 which forces the material into the injector 28 from whence it is redispersed into the oil vapors to be cracked.

15 The screw conveyor 66 may have a compression screw for imposing a pressure necessary to overcome the pressure drop through the cracking system. In such case the screw conveyor 48 may only supply sufficient pressure to overcome the flow resistance through the regenerating section of the equipment. However, the amount of pressure necessary to overcome flow resistance 20 may be provided by a single screw conveyor located either in the cracking or in the regenerating section of the equipment.

25 While screw conveyors have been described for supplying the required pressure for overcoming flow resistance, it will be understood that any other equivalent devices may be employed. For example, the catalyst passing from the cracking to the regenerating sections of the equipment and vice versa may be passed through double bell 30 hoppers or other equivalent chambers in which the required pressure may be built up by means of a gas or steam.

35 The catalyst introduced into the oil stream may be at substantially the final regenerating temperature such as 1000°. It is preferred to introduce the catalyst into the oil vapors at a temperature not materially below the temperature of the oil vapors and preferably somewhat above so that a part of the heat necessary for cracking 40 may be supplied by the catalyst. Likewise, the catalyst introduced into the regenerating gas in the injector 48 is preferably at the final cracking temperature which may be, for example, of the order of 800-900° F.

45 In accordance with the present invention, the pressure drop between the cracking and regenerating portions of the equipment is preferably maintained at the minimum necessary to overcome the resistance through the equipment and should be less than one atmosphere. Furthermore, it is preferred to maintain both the cracking and regenerating portions of the equipment under a total pressure of the order of from 2 to 50 20 atmospheres gage while maintaining the partial pressure of the oil vapors leaving the cracking zone of the order of 1 atmosphere or less. This may be accomplished by supplying a part of the total pressure in the cracking section with an inert or non-cracking gas introduced at any one or more of the various points described or at other points in the system.

55 As a further alternative such inert gas may comprise the residual gases formed during the cracking operation. For example a portion of the gases separated in the receiver 43 may be recycled through line 67 and compressor 68 and combined with the oil stream passing to the heating coil 12 through line 69 or to the oil stream 60 passing to the injector 28 through line 70.

65 The invention thus makes possible the crack-

ing of oils in the presence of a powdered catalyst without the necessity of providing mechanism between the cracking and regenerating circuits for building up a substantial differential pressure therebetween.

Having described the preferred embodiment of the invention it will be understood that it embraces such other variations and modifications as come within the spirit and scope thereof.

What is desired to be protected by Letters Patent is:

1. In the catalytic cracking of hydrocarbon oil wherein the catalyst is suspended in powdered form in a stream of oil vapors to be converted and the resulting stream passed through a cracking zone and wherein the catalyst after separation from the cracked products is passed through a regenerating zone; the improvement which comprises maintaining both the cracking and the regenerating zones under a total pressure in excess of two atmospheres and maintaining a partial pressure of oil vapors within the said cracking zone at not substantially exceeding one atmosphere.

2. A method of cracking hydrocarbon oil which comprises passing a mixture of hydrocarbon oil vapor boiling above the gasoline boiling range, diluent gas and finely divided catalyst through a cracking zone maintained at cracking temperature, subjecting said mixture to a substantial superatmospheric pressure during passage through the cracking zone, regulating the molar concentration of oil vapors and diluent gas to maintain the oil vapor pressure not substantially in excess of 1 atmosphere, maintaining said mixture within said cracking zone for a period sufficient to obtain the desired cracking, thereafter separating the catalyst from the cracked products and diluent gas, separating a motor fuel fraction from the cracked products, passing the separated catalyst through a regenerating zone wherein combustible deposits formed during the cracking operation are removed therefrom, maintaining the regenerating zone under a pressure substantially equal to total pressure maintained in said cracking zone and returning regenerated catalyst to said cracking zone.

3. A method of cracking hydrocarbon oil which comprises passing a mixture of hydrocarbon oil vapors boiling above the gasoline boiling range, diluent gas and finely divided cracking catalyst

through a cracking zone maintained at cracking temperature, subjecting said mixture to a total pressure of at least two atmospheres during passage through said cracking zone, regulating the molar concentration of the oil vapors and diluent gas to maintain the oil vapor pressure not substantially in excess of one atmosphere, maintaining said mixture within said cracking zone for a period sufficient to obtain the desired cracking thereof into lower boiling hydrocarbons suitable for motor fuel, thereafter separating the catalyst from the cracked products and diluent gas, separating a motor fuel fraction from the cracked products, passing the separated catalyst through a regenerating zone wherein combustible deposits formed during the cracking operation are removed therefrom, maintaining the regenerating zone under a pressure substantially equal to the total pressure maintained in the cracking zone, and returning regenerated catalyst to said cracking zone.

4. A method of cracking hydrocarbon oil which comprises passing a mixture of hydrocarbon oil vapors boiling above the gasoline boiling range, diluent gas and finely divided cracking catalyst through a cracking zone maintained at cracking temperature, subjecting said mixture to a total pressure of at least two atmospheres during passage through the cracking zone, regulating the molar concentration of the oil vapors and diluent gas to maintain the oil vapor pressure not greater than about one atmosphere, maintaining said mixture within said cracking zone for a period sufficient to obtain the desired cracking thereof into motor fuel constituents, thereafter separating the catalyst from the cracked products and diluent gas, separating a motor fuel fraction from the cracked products, suspending the catalyst so separated in a regenerating gas, passing the resulting suspension through a regenerating zone wherein combustible deposits formed during the cracking operation are removed therefrom, maintaining the regenerating zone under a total pressure substantially equal to the pressure maintained in the cracking zone, separating regenerated catalyst from the regenerating gas, and returning the regenerated catalyst to the cracking zone.
